ATTORNEY.

UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed April 9, 1920. Serial No. 372,445.

To all whom it may concern:

Be it known that I, JOHN WALDHEIM, a citizen of the United States, residing in Elizabeth, in the county of Union and State 5 of New Jersey, have invented certain new and useful Improvements in Typewriting Machines, of which the following is a specification.

This invention relates to typewriting machines, and more particularly to the kind used for continuous billing, shown in the patent to Wernery & Smith No. 1,132,055, of March 16, 1915, in which a folded pack of work-sheets or webs with interleaved carbon-sheets may be fed around a platen to the printing point; the carbon-sheets being attached to a carrier to enable them to be shifted to untyped portions of the work-webs.

20 The webs or continuous work-sheets usually have printed forms thereon and may be drawn forwardly, after they have been typed, to a gage, prior to severing the typed forms from the pack of continuous sheets.

25 The printed forms on the various sheets may include instructions differing from each other, according to the several uses for which the copies may be required. For example, the original or outer sheet may be

30 sent to the customer, while the various copies may be intended for different departments. It is therefore desirable to be able to readily distinguish the various copies to facilitate their sending to the various places 35 for which they are intended. To do this, it has been proposed to print the ruled forms and their respective instructions on the various continuous work-sheets in different colors. It has also been proposed to use

40 work-sheets in which the materials are of different colors, in which case the forms may be printed thereon with the same colored ink. This last-mentioned method, however, necessitates the making of different work-sheets separately, due to the differently colored materials.

The object of the present invention is the provision of means to accomplish the desired result without necessitating the printing 50 of the forms with different kinds of ink, or the making of the work-sheets of differently colored materials.

For this purpose, I arrange to provide the various forms with marks of identifica-

tion, after the work-sheets have been inserted in the machine. 55

To this end, the interleaved carbon-sheets may be provided at their leading edges with comparatively narrow fields having colors which differ from the bodies of the carbon-sheets, each comprising a wide field which may be black in color; the colors of the narrow fields differing also from each other. The narrow fields of the carbon-sheets may be brought to the printing point when the carbon-sheets are retracted, prior to the writing of a new set of forms, so that the first entry typed on each set of forms, which may be an order number, may appear in different colors on the various forms. 70

In typing the body of the forms, it is sometimes desired to make certain entries other than the first entry stand out from the others which are typed in black. For this purpose, such entries may be typed on the 75 outer sheet through the red field of the usual bichrome ribbon. To have this entry appear differently on the various carbon copies, the carbons may be shifted relatively to the work-sheets, prior to making the entries, to 80 bring the narrow fields of different colors to the printing point.

In some cases, where instead of having such entries appear in different colors, it is desired to have them appear in red as on 85 the original, each carbon-sheet may be provided with another narrow field which may be red in color and adjacent to the other narrow field, all of the red fields being collectively shiftable to the printing point at 90 will.

In the continuous billing machine, it is also desirable, at times, to type on the outer work-sheet, which is done through the usual ribbon, without reproducing the typewritten matter on the carbon copies. 95

For this purpose, provision is made to permit the carbon-carrier to be retracted to an abnormal position to bring the leading edges of the carbon-sheets below the printing point, thereby rendering them ineffective for copying purposes. 100

To permit the carbons to be retracted to bring the narrow fields to the printing point, or to permit the carbon-sheets to be 105 rendered ineffective, there may be provided a plurality of settable stops to co-operate with a relatively fixed stop to arrest the

carbon-carrier in different positions when reTRACTING the carbon-sheets.

The invention further relates to means to facilitate the assembling of the carbon-sheets on the various holders of the carbon-carrier, so that the differently colored fields of the various carbon-sheets may register with each other.

The invention may also be used to increase 10 the use of the carbon-sheets since the carbon-carrier may be arrested in different positions, thus enabling the spaces between the type positions on the carbon-sheets to be used.

15 Other features and advantages will hereinafter appear.

In the accompanying drawings,

Figure 1 is a diagrammatic perspective view of part of the machine, showing the 20 invention applied thereto.

Figure 2 is a plan view, showing two superposed carbon-sheets.

Figure 3 is a diagrammatic side view, showing the black fields of the carbons in 25 use.

Figure 4 is a view similar to Figure 3, showing the narrow field or fields of different colors in use.

Figure 5 is a view similar to Figure 3, 30 showing the carbons retracted with their leading edges below the printing point to render them ineffective.

Figure 6 is a fragmentary perspective view, showing a folded pack of work-sheets 35 with interleaved carbon-sheets, each carbon-sheet having a plurality of narrow fields near its leading edge.

Figure 7 is a side view of the machine, 40 partly in section, showing the invention applied to increase the use of carbon-sheets, the work-sheets and the carbon-sheets being in position after tearing off a typed set of forms.

Figure 8 is a view similar to Figure 7, 45 but showing the parts after the carbon-carrier has been retracted with a different stop set into effective relation with the relatively fixed stop.

Figure 9 is a sectional front view of a 50 portion of the carbon-carrier, showing the settable stop-member carried thereby.

Figure 10 is a perspective view as seen 55 from the back of a portion of the carbon-carrier with the settable stop-member and the relatively fixed stop.

Continuous work-sheets 15, which may be folded to form a pack 16, as shown in Figure 6, and shown as separate sheets, for clearness, in Figures 1 and 7, may be inserted in the machine. The work-sheets may be led from any suitable source of supply over a rear rail 17 of an auxiliary carriage frame 18, comprising two end bars or rails 20 and 21, connected to travel with a platen-carriage 22.

The work-sheets 15 may be extended forwardly over a carbon-sheet-carrier or carriage 23, supported on the end rails 20 and 21. Carbon-sheets 24 are interleaved between the work-sheets 15, and extend forwardly from the carbon-sheet holders 25 on the carbon-carrier. The work-sheets and the carbon-sheets pass over a shaft 26, supported on the platen-carriage, and extend downwardly around a platen 27 and between feed-rolls 28. At the front of the platen, the work-sheets and the carbon-sheets are guided upwardly past the printing point, so that they may be typed upon by the type-bars 29, the outer work-sheet receiving its 75 impressions through an inking ribbon 30, which may have a black field 30^a and a red field 30^b, while the inner work-sheets receive their impressions through the interleaved carbon-sheets 24. The platen is mounted on a platen-shaft 31, rotatably mounted, so that the work-sheets may be line-spaced, in a frame 32, which may be swung about the axis of a rod 33, supported in suitable brackets 34 on the platen-carriage, for a purpose 80 85 hereinafter described.

To line-space the platen after each line is typed on the work-sheet, there may be provided the usual line-space lever 35, which swings, when operated, about a pivot 36, to cause a toe 37 thereon to push a line-space slide 38 rearwardly. The line-space slide is provided with a pawl 40 to engage the teeth 41 of a ratchet-wheel 42 to rotate a shaft 43, supported in the carriage 22. The shaft 43 100 has secured thereto, at its inner end, a gear-wheel 44, meshing with a pinion 45, revolvably supported on the rod 33; said pinion being broad enough to engage with a gear-wheel 46, adjacent to the gear-wheel 44. The gear-wheel 46, however, is secured to the platen-shaft 31, which is normally in alignment with the line-space shaft 43. Thus, as the gear-wheel 44 is rotated, the line-space movements are transmitted 105 110 through the pinion 45 and the gear-wheel 46 to the platen to feed the work-sheets forwardly.

The work-sheets 15 may be furnished with printed forms thereon, which are of 115 equal length and extend lengthwise of said sheets. After the entries are made on each set of forms, the set may be severed by a knife 47 (Figure 7), supported in the swing-frame 32, and extending lengthwise 120 of the platen 27. Since the printed forms are of successive equal lengths, and the number of entries may vary on the different sets of forms, it is necessary to first gage the forms prior to severing. It is also desirable to retract the carbon-sheets 24 to bring them to the next succeeding set of forms, and their leading edges below the cutting edge of the knife before severing. To facilitate the shifting of the carbon- 125 130

sheets relatively to the work-sheets, the platen may be displaced by the swing-frame 32, which is locked in printing position (Figure 7), by hooks 48 and 50 on the shaft 26, which is spring-operated to hold the hooks 48 and 50 over studs 51 on the swing-frame.

To release the swing-frame the hook 50 is provided with a finger-piece 52, which may 10 be pushed rearwardly to move the hooks 48 and 50 out of holding relation with the studs 51 on the swing-frame. The typist then grasps a front paper-table 53, forming part of the swing-frame, to swing said 15 frame about the axis of the rod 33, to raise the platen 27 sufficiently to permit the pack of work-sheets and carbon-sheets to be straightened out by pulling the pack forwardly until the leading edges of the work- 20 sheets are arrested by an adjustable gage 54, on a gage-bar 55, the latter at this time occupying a substantially horizontal position. The carbon-sheet carriage or shifter 23 is pushed rearwardly by a handle 56 25 until arrested by a stop-member 57 engaging a stop 58 on the rail 20 of the auxiliary carriage frame 18.

The frame 32 is then swung back to lower the platen to typing position, while 30 the work-sheets are held against the gage-bar with their leading edges against the gage 54. After the frame has been swung back, the set of typed or finished forms may be severed from the pack, by pulling them 35 crosswise of the knife 47.

Provision is made to make distinguishing marks on the various typewritten forms after the sheets have been inserted in the machine. This may be done on each set of 40 forms, while typing thereon. To do this, the leading edges of the carbon-sheets 24 (which, it will be remembered, extend forwardly from the holders on the carbon-carriage), may be provided each with a comparatively narrow field or coated surface 45 60, differing in color from the color of the coating which may cover the balance of the carbon-sheets to form wide fields 61, which may be black in color. The narrow fields 50 60, differing in color from each other, may be brought to the printing point when the carbons are retracted or shifted relatively 55 to the work-sheets. For this purpose, the stop-member 57 is provided, which may be pivoted to a bracket 62 on the carbon-carrier 23, so that a co-operative stop 63 thereon 60 may be set into range of the stop 58 to engage, on the return stroke of the carbon-carrier, with the relatively fixed stop 58, thus bringing the differently colored 65 fields 60 to the printing point (Figure 4), or, in other words, rendering them effective. The first entry may then be typed and copied on the inner sheets in different colors through the narrow fields 60 of the

carbons, the different colors serving as distinguishing marks for the various work-sheets. The entry on the outer work-sheet may be made through the black field of bichrome ribbon 30. The line-space handle 70 35 is next operated to feed the work-sheets and the carbons forwardly, thus bringing the black fields 61 of the various carbons into use for the balance of the entries to be made. 75

It should be understood that the fields of different colors may be rendered effective at any time. For example, if it is desired to make an entry appear in different colors after several entries have been typed, the 80 platen may be lifted to permit the carbons to be shifted to bring the narrow fields 60 to the printing point, but, instead of pulling the work-sheets to the gage 54, they may be held tightly against the table 53, 85 or gage-bar 55, while the carbon-sheets are shifted by pushing the carbon-carrier 23 rearwardly, the stop 63 having previously been set into effective relation with the fixed stop. The platen is then swung down, when 90 the entries to appear in different colors on the various work-sheets may be made, after which the succeeding entries appear in the same color as the preceding entries. 95

As previously stated, the body of each 100 carbon-sheet may be black, so that the greater part of the typewritten matter may appear in black on the various forms. It should be understood, however, that the differently colored fields may extend over the greater part or the whole surface of the carbon-sheets. 100

The carbon-sheets 24 may be held on their respective holders 25, by clips 64, pivotally supported on the holders. It will 105 be seen by an inspection of Figure 1 that the carbon-sheet holders 25 are placed side by side and successively further away from the platen. It is desirable, however, to assemble the carbon-sheets on the holders so 110 that the fields 60 on the various carbon-sheets may register with each other. For this purpose, each carbon-sheet may be provided at its edges with markings 59, so that the corresponding markings on the opposite 115 sides of the carbon-sheets may be used to position the latter on the holders by bringing the markings in line with the back edges of the holders. The markings are spaced apart from each other distances 120 equal to the distance between the back edges of the successive holders, so that any carbon-sheets may be secured to any one of the holders, the set of markings used to position the carbon-sheet depending on the 125 position the holder is to occupy on the carbon-sheet-carrier when attached thereto.

Sometimes it is desirable to type a set of forms without distinguishing marks. To do this, the stop-member 57 may be set 130

to a different position to bring a stop 65 thereon into effective relation with the fixed stop 58, so that the carbon-carrier may be arrested earlier during a carbon-sheet-retracting operation, so that the leading edges of the black fields 61 are brought to the printing point; the differently colored fields thus falling short of being brought into use, as shown in Figure 3. The set of forms 10 may now be typed to have the typewritten matter appear on the various copies in the same color.

It is also desired at times to typewrite matter on the outer work-sheet which is not to appear on the carbon copies. For this purpose, provision is herein made to shift the carbon-sheets 24 during the carbon-retracting operation to bring their leading edges below the printing point, thus 20 rendering them ineffective, as shown in Figure 5. To do this, the settable stop-member 57 is provided with a stop 66, which may be set into effective relation with the relatively fixed stop 58, to permit the carbon-carriage to be moved rearwardly a greater extent to an abnormal position, to bring the leading edges of the carbon-sheets out of range of the printing type-bars 29. The operator may proceed to type the entry 30 which may be made on the outer sheet through the ribbon 30, without transferring the type impressions to the inner work-sheets.

It should be understood that the differently colored fields 60 of the carbon-sheets 35 may be made wider, so that they may remain in use for several line-space movements of the platen. The leading edges of the carbon-sheets may also be drawn a greater distance below the printing point, so as to allow several lines to be typed on the outer sheet before the carbons are brought into use. This may be done by having the stops 65, 63 and 66 spaced further apart from each other to increase the extent of the rearward movement of the carbon-carrier.

To facilitate the setting of the stop member 57, so that the carbon-sheet-carrier may be arrested to render the black fields 61, or the differently colored fields 60 of the carbon-sheets effective, or bring the carbon-sheets to a non-copy or ineffective position, indicating means may be provided. The 50 indicating means may comprise an index plate 62^a forming the upper part of the bracket 62, and having the marks "B", "D" and "N", respectively, for the black color, distinguishing colors and non-effective positions of the carbon-sheets; the stop-member 57 being settable by means of a handle 67 and an indicator 68, which may point to "B", "D" or "N". To hold the 55 settable stop-member 57 in any one of its positions, it may be slightly resilient and

provided with a projection 70, to snap into any one of a plurality of holes 71 in the supporting bracket 62.

To enable copying on the various work-sheets in red or in various colors at the 70 same time, the carbon-sheets 15 may each be provided with two narrow fields 60 and 72, as shown in Figure 6, thus forming sets on the various carbon-sheets, the set of fields 72 nearest the leading edges of the carbons 75 being of the same color, which may be red, thus differing from the black fields 61 of the carbons and from the differently colored fields 60. It will be seen that with appropriate markings on the index plate 62^a, the 80 stop-member 57 may be set, so that the carbon-sheets may be selectively positioned so as to bring the various sets of fields 61, 60 or 72 to the printing point.

A further use of the invention may be to 85 increase the period of usefulness of the carbon sheets. This may be done by providing the settable stop-member 57 with two stops 73 and 74, as shown in Figures 7 to 10, inclusive; the stop-member 57 being settable 90 from the position in Figure 7 to the position in Figure 8, so that after the carbon-sheets 24, which may have complete black surfaces, have become worn by the type-bars 29, the carbon-carriage 23 may be permitted to move back a little further, as in Figure 8, and be arrested by the stop 74, thus permitting the unused portions 95 between the used portions of the carbon-sheets to be brought into use, the unused portions 100 being brought successively to the printing point by line-spacing the platen 27.

It will be seen that the stop 58 is not merely a stop but that it also serves as a 105 master gaging device, and that since it determines a definite location for the carbons while the gage 54 determines a definite position for the work-webs, the two gages 54 and 58 co-operate to locate the work-webs and carbons definitely with relation to each 110 other. The stepped stop device serves as an auxiliary gage to vary, by mechanically predetermined amounts, the position of the carbons relatively to the master gaging device 58, such variations corresponding to 115 the widths of the narrow color fields.

Variations may be resorted to within the scope of the invention, and portions of the improvements may be used without others.

Having thus described my invention, I 120 claim:

1. In a typewriting machine, the combination with a platen, a releasable feeding device, to receive and line-feed work-sheets, of an interleaved copying element having a 125 plurality of fields of different colors, and means settable to a plurality of operative positions to shift the copying element relatively to said work-sheets to selectively render any one of the fields effective. 130

2. In a typewriting machine, the combination of a revoluble platen, a releasable feeding device, an interleaved carbon-sheet having a plurality of fields of different colors, means to shift the carbon-sheet between and relatively to said work-sheets, and means to selectively locate the carbon-sheet with different fields at the printing point. 70
3. In a typewriting machine, the combination of a revoluble platen, a carbon-sheet having a plurality of fields of different colors mounted to be interleaved with work-sheets and fed around the platen therewith, a carbon-sheet carrier to shift the carbon-sheet between and relatively to the work-sheets, a fixed carbon-gaging device, and means settable to mechanically determine the position to which the carbon-sheet is moved with reference to the gaging device, 75 and thereby to select the field of the carbon-sheet to be rendered effective by the shifting of the carbon. 80
4. In a typewriting machine, the combination of a revoluble platen, a carbon-sheet having a plurality of fields of different colors mounted to be interleaved with work-sheets and fed around the platen therewith, a carbon-sheet carrier to shift the carbon-sheet between and relatively to the work-sheets, and arresting means for said carbon-sheet carrier including a stop and a device settable to select the field of the carbon-sheet to be rendered effective by the shifting of the carbon-carrier against the stop. 85
5. In a typewriting machine, the combination of a revoluble platen around which work-sheets, and an interleaved carbon-sheet having a plurality of fields of different colors, may be fed, a carbon-sheet-carrier to shift the carbon-sheet relatively to the work-sheets, supporting means for said carbon-sheet-carrier, a relatively fixed stop on said supporting means, and a settable device on said carbon-sheet-carrier to determine the field of the carbon-sheet to be effective when the carbon-sheet-carrier is arrested by the settable device engaging with the stop. 90
6. In a typewriting machine, the combination of a platen to receive work-sheets to be typed upon, a ribbon shifter to render effective, for type impressions on the outer sheet, any selected field of a ribbon having a plurality of fields of different colors, a carbon-sheet-carrier to control a carbon-sheet interleaved between the work-sheets, said carbon-sheet having a plurality of fields of different colors corresponding to the colors of the field of the ribbon, and means to determine shifted positions of the carbon-sheet-carrier to selectively render effective the fields of different colors, whereby different, correspondingly colored fields of the ribbon and of the carbon-sheet may be made effective together. 105
7. In a typewriting machine, in combination, a platen, a reciprocable carbon-sheet-carrier, and means to check the rearward movement of the carrier before a carbon-sheet thereon has been retracted below the printing line, said checking means being releasable to permit withdrawal of the carbon-sheet below the printing line, and being automatically effective when so released to check the carbon-carrier when the carbon-sheet has been withdrawn a short distance below the printing line. 110
8. In a typewriting machine, the combination with a revoluble platen over which work-sheets, with an interleaved carbon-sheet having a plurality of fields of different colors, may be fed, of a carbon-sheet-carrier, and means to determine the starting position of the carbon-sheet, including an adjustable gaging device and settable means on the carbon-sheet-carrier co-operating with the gaging device, to vary the starting position of the carbon-sheet, so that any one of the fields of the carbon-sheet may be brought to the printing point. 115
9. The combination with a platen around which work-sheets, with an interleaved carbon-sheet having at its leading edge a narrow field of distinctive color, may be fed relatively to a common printing point, of a carbon-sheet-carrier operable to displace the carbon-sheet relatively to the work-sheets, a stop, means for adjustably securing said stop in position according to the length of the carbon sheet and a co-operative stop to engage the first-mentioned stop and arrest the carbon-sheet-carrier in its normal position with the leading edge of the main portion of the carbon-sheet above the printing point, said co-operative stop being settable to a position to permit the carbon-sheet-carrier to be shifted to an abnormal position to bring the narrow field of the carbon-sheet to the printing point. 120
10. In a typewriting machine, in combination, a platen, a reciprocable carbon-sheet-carrier, and means to check the rearward movement of the carrier before a carbon-sheet thereon has been retracted past the printing line, comprising a gaging stop and a series of stops in fixed relation to each other for checking the rearward movement of the carrier at fixed points and rendered effective at will to determine different transverse fields of the carbon-sheet to be positioned at the printing line, and to permit the carbon-sheet to be withdrawn past the printing line. 125
11. In a typewriting machine, in combination, a platen, copying elements having a plurality of fields of different colors mounted to be interleaved with work-sheets and line-fed around the platen therewith, and means for varying at will the colors of the copies made on the different work-sheets when a line is typed on the outer sheet, the 130

color-varying means comprising means for shifting said copying elements between and relatively to the work-sheets, and gaging means to determine the positions of said copying elements for copying in the different colors.

12. In a typewriting machine, in combination, a platen, a carriage in which said platen is supported, a reciprocable carbon-carrier, a stop adjustable on said carriage, in accordance with the lengths of the carbon-sheets to be used, and a stop device mounted at a fixed point on said carrier, said stop device being settable to engage said stop at different positions of the carrier and to vary the rearmost positions of the carrier in accordance with the settings of said stop device.

13. In a typewriting machine, in combination, a platen, a traveling carriage on which said platen is mounted, a reciprocable carbon-carrier, a stop on said carriage, and a stepped interponent shiftable to different positions to vary the rearmost position of the carrier with reference to the stop.

14. In a typewriting machine, the combination with a revoluble platen around which work-sheets, with an interleaved carbon-sheet, may be fed, of a carbon-sheet-carrier to retract the carbon-sheet relatively to the platen, means, including a gaging stop adjustable in accordance with the length of the carbon-sheet and a settable device on the carbon-sheet-carrier to co-operate therewith, to vary the starting position of the carbon-sheet, and an index plate and a detent for the settable device.

15. In a typewriting machine, the combination with a revoluble platen over which work-sheets, with an interleaved carbon-sheet, may be fed, of a carbon-carrier, and means, including settable means on the carbon-carrier, to vary the starting position of the carbon-sheet.

16. In a typewriting machine, the combination with a platen around which work-sheets, with an interleaved carbon-sheet, may

be fed, of a carbon-sheet-carrier to retract the carbon-sheet relatively to the work-sheets, means, including a stop and a plurality of co-operating stops on said carbon-sheet-carrier, to arrest the carbon-sheet-carrier, and means to selectively set any one of the co-operating stops into effective relation with the first-mentioned stop. 50 55

17. In a typewriting machine, a platen, a carbon-sheet having a plurality of transverse color-fields mounted to be interleaved with work-plies and fed around the platen, a carbon-carrier for shifting the carbon-sheet relatively to the work-plies, a master gaging device settable in accordance with the length of the carbon-sheet, and an auxiliary gaging device co-operating with the master gaging device and settable to vary by a mechanically-determined amount corresponding to the extent of one of the color-fields the position of the carbon-sheet when the master and auxiliary gaging devices are brought into co-operating engagement. 60 65 70

18. In a continuous billing typewriting machine, a platen, a carbon-carrier, a plurality of superposed carbon-sheets mounted on the carbon-carrier for movement toward and from the platen, between the plies of a fan-fold work-form, said carbon-sheets having at their leading margins narrow superposed color-fields of different colors, whereby the impressions typed through them will be caused to distinguish from each other the various plies of the fan-fold form, a gage to locate the fan-fold form in predetermined position with reference to the platen to cause the first writing-line thereof to be located in writing-position, and means for arresting the carbon-carrier to locate the distinguishing color-fields of the carbon-sheets in register with the first writing-line of the fan-fold form. 75 80 85
